(57) **CLAIM**

The ornamental design for an unload spout for agricultural vehicle as shown and described.

DESCRIPTION

FIG. 1 is a perspective view taken from the top and rear sides of an unload spout for agricultural vehicle showing our new design;

FIG. 2 is a rear view thereof;

FIG. 3 is a front view thereof;

FIG. 4 is a left side view thereof;

FIG. 5 is a right side view thereof;

FIG. 6 is a top plan view thereof; and,

FIG. 7 is a bottom plan view thereof.

The broken lines illustrate portions of the unload spout for agricultural vehicle that form no part of the claimed design.

1 Claim, 6 Drawing Sheets
